US0D1012701S

(12) **United States Design Patent** (10) Patent No.: **US D1,012,701 S**
(45) Date of Patent: ** Jan. 30, 2024

(54) **CUP COVER**

(71) Applicant: **ReCup GmbH**, Munich (DE)

(72) Inventors: **Max Ceburkov**, Munich (DE);
Ferdinand Schütze, Munich (DE);
Nick Tränkle, Munich (DE); **Sebastian Schmidt**, Munich (DE); **Michael Berling**, Munich (DE)

(**) Term: **15 Years**

(21) Appl. No.: **35/516,122**

(22) Filed: **Jan. 12, 2023**

(80) **Hague Agreement Data**

Int. Filing Date: **Jan. 12, 2023**

Int. Reg. No.: **DM/226108**

Int. Reg. Date: **Jan. 12, 2023**

Int. Reg. Pub. Date: **Jan. 27, 2023**

(30) **Foreign Application Priority Data**

Jul. 13, 2022 (EM) 009085822-0001

(51) **LOC (14) Cl.** **09-07**

(52) **U.S. Cl.**

USPC **D9/447**; D7/396.2; D9/454

(58) **Field of Classification Search**

USPC D9/434-436, 499, 440, 443, 447, 449, D9/454; D7/392.1, 396.2

CPC A47G 19/22; A47G 23/02; B65D 23/10; B65D 23/12; B65D 41/04; B65D 47/06

See application file for complete search history.

(57)

CLAIM

The ornamental design for a cup cover, as shown and described.

DESCRIPTION

1. Cup cover

1.1: Perspective top view

1.2: Perspective bottom view

1.3: Front view

1.4: Back view

1.5: Side view

1.6: Top view

1.7: Bottom view

1 Claim, 7 Drawing Sheets
